UNITED STATES PATENT OFFICE.

ALBERT W. MORRIS, OF SPRINGFIELD, MASSACHUSETTS, ASSIGNOR TO KENNETH W. McNEIL, OF BRIDGEPORT, CONNECTICUT.

CASTING MACHINE.

Application filed December 31, 1919. Serial No. 348,658.

To all whom it may concern:

Be it known that I, ALBERT W. MORRIS, a citizen of the United States of America, residing at Springfield, in the county of 5 Hampden and State of Massachusetts, have invented certain new and useful Improvements in Casting Machines, of which the following is a specification.

This invention relates to an improved machine for casting articles in dies or molds under pressure. While the machine is generally used for casting the various metals, alloys and compositions, it is not limited to such use and may be used, if desired, for 15 casting various other molten substances or liquids which will later solidify.

The broad object of the invention is to provide a casting machine which is wholly automatic in operation. That is the various mold parts, as the cope, jaws, and so forth including the cores, if any; are assembled, the assembled mold moved to and clamped against the crucible containing the substance to be cast, the metal or other substance therein placed under pressure and then discharged into the mold, and the reverse operations accomplished all automatically in properly timed and coordinated relation.

Another object of the invention is to provide automatically controlled fluid pressure means for effecting the various operations described.

Another object of the invention is to provide fluid pressure means for moving the various mold parts, characterized by the yielding effect of such operating means over anything mechanical, and by the variable stroke available to meet the varying conditions encountered.

Another object of the invention is to provide core pulling devices which operate by fluid pressure means, characterized in that the core may be gradually extracted from the casting with comparative gentleness, especially at the start of the extracting operation, the fluid pressure operating means in practical effect feeling its way during the withdrawal of the core.

Another object of the invention is the provision of fluid pressure means for effecting the closing of the discharge valve

of the crucible. While such means may also be, and preferably is, utilized for opening such valve, there is special utility in 55 the closing operation for, by proper control of the fluid pressure operating means, the valve may be made to close very forcibly and driven into the discharge orifice with a ram effect, which intensifies the pressure 60 on the metal and forces it into all the crevices of the mold.

Another object of the invention is the provision of valves to control the admission and exhaustion of the fluid under pressure 65 to and from each cylinder. The exhaust and inlet valves are automatically operated from a common source and may thus be co-ordinated one with the other to secure a desirable cushion effect at the end of travel 70 of the various elements of the machine.

Another object of the invention is to provide improved shields for protecting the operator from possible injury by escaping molten metal.

Another object of the invention is to provide a receiver, preferably in the nature of a trough, which automatically moves in under the discharge nozzle of the crucible to receive the drip therefrom and convey 80 it to a suitable receptacle and which enables the crucible to be quickly emptied, when desired.

Another object is to provide upon the mold carrying bed various devices, which 85 may be used for moving the mold parts, including the cores, and which are provided in flexible arrangements capable of being varied within wide limits to adapt the machine to widely varying types of molds.

Another object of the invention is to provide automatic means for cleaning the discharge nozzle of the crucible prior to each casting operation.

Other objects and advantages will appear in the following description and in the illustrative embodiment of the invention in the accompanying drawings, in which—

Fig. 1 is a side elevational view of a machine embodying the invention;

Fig. 2 is a sectional elevation thereof;

Fig. 3 is a fragmentary front elevational view showing the mounting of the front shield;

Fig. 4 is an enlarged sectional plan view taken on the line 4—4 of Fig. 2;

Fig. 5 is an enlarged fragmentary sectional elevation illustrative of the valve for the crucible;

Fig. 6 is an enlarged sectional plan view taken on the line 6—6 of Fig. 1;

Fig. 7 is a sectional plan view taken on the line 7—7 of Fig. 1;

10 Fig. 8 is an enlarged plan view of the clutch mechanism units;

Fig. 9 is a fragmentary elevational view of one of the clutch operating levers;

15 Figs. 10 and 11 are enlarged end and sectional elevational views, respectively, of a typical valve unit;

Fig. 12 is a plan view taken on the line 12—12 of Fig. 11;

Fig. 13 is a sectional elevation of a typical fluid pressure actuating means;

Figs. 14 and 15 are sectional and elevational views, respectively, of a modification in the valve structure shown in Figs. 10 and 11;

25 Fig. 16 is a diagrammatical perspective view showing conventionally the various valves, fluid pressure cylinders and the connections therebetween;

30 Figs. 17 and 18 are fragmentary plan and cross-sectional views of the mold-carrying bed and adjacent parts, illustrating particularly the adaptation of the machine to one particular type of mold;

Fig. 19 is a fragmentary perspective view 35 of a cam bar and its reciprocable operating rod;

40 Figs. 20 and 21 are views, taken generally similarly to Figs. 17 and 18, showing the adaptation of the machine to a second type of mold;

Fig. 22 is a sectional elevation illustrative of the controlling device for the mold cleaning means; and

45 Fig. 23 is a bottom plan view of the furnace casing illustrative of the nozzle cleaning means.

The general frame structure of the machine will first be described. A represents a suitable base plate to which are secured in 50 spaced parallel relation two upstanding side frames B. Such frames are tied together at their upper ends by a bridge-like member C, which has an integral upwardly extending hollow cylindrical portion D forming

55 the casing of the furnace to be later described. On the inner face of each side frame B are upper and lower longitudinal flanges a and b which are arranged in spaced parallel relation and afford a horizontal

60 channel c. Each of these channels is adapted to receive a lifting bar, to be later described, but such bar occupies only a portion of channel c, leaving a rear portion (right hand as viewed in Fig. 2) unoccupied.

65 In the rear portion of channel c there

is located a supporting frame E, which extends laterally across the side frames B, rests upon the lower flanges b and is suitably secured thereto. Below frame E are two other parallel frames F and G, constituting 70 supports for the upper and lower clutch mechanisms respectively. All three frames E, F, and G are suitably held together, as by the bolts d illustrated.

The furnace will next be described with 75 particular reference to Figs. 1, 2, 4 and 6. Its shell is constituted by the hollow cylindrical portion D, just described, such shell having a refractory lining of suitable material, such as an outer lining e of a suitable 80 refractory material sil-o-cel and an inner lining f of fire brick (Fig. 6). The shell D is capped by a cover g, which, as well as the lined shell, affords a through opening to receive a crucible h for the reception of the 85 fluid metal. The shell D and its linings e and f are provided with suitable openings i, preferably directed tangentially relatively to the crucible h, to receive burners such as are conventionally shown at j in Figs. 6 and 90 16. The burners j are provided with suitable supply pipes k and are supported by such pipes and suitable brackets from the bridge member C described. By the use of burners, located as described, the flames are 95 caused to travel circumferentially about the crucible h and thus a substantially uniform distribution of heat is insured. Suitable vent openings l are provided through cover 100 g and the lining f for the furnace, such openings communicating with the annular passage between crucible h and lining f.

The crucible h which receives the metal or other substance to be cast, is suspended from cover g within the furnace and has an outlet or nozzle m at the lower end thereof. A cover n is suitably secured to the top of crucible h to tightly close the otherwise open top thereof. A part of cover n (Figs. 2 and 4) is partitioned off to provide a chamber o, 105 which has communication with the interior of the crucible only by way of long, arcuate and relatively narrow slots p located near the outer periphery of the cover. Leading radially into chamber o are diametrically 110 disposed inlet and outlet pipes q and r by means of which fluid under pressure, preferably compressed air, is admitted to and exhausted from the crucible h, respectively. By admitting the compressed air into chamber o, rather than directly into the crucible h, the lower wall of the chamber acts as a baffle, causes the air to spread out and be more uniformly distributed over the surface of the metal as it enters through slots p. 115 More important still, the air entering through slots p is caused to impinge on the flaring upper part of crucible h, whereby it is deflected away from and prevented from directly impinging on the fluid therein. The 120 125 130

- cover *n* is provided with a filling opening, normally closed by the removable plug *s*, as shown, which communicates directly with crucible *h* and due to the flaring upper end of crucible *h*, such opening may readily be made large enough to permit the insertion of the operator's hand for purposes to later be described and the insertion of large pieces of metal as defective castings and such.
- 10 The outlet of the crucible *h* is closable by a valve *t* which is mounted for vertical reciprocation in the cover *n*. The valve *t* proper is made of refractory material and is detachably connected, as by the screw threads 15 illustrated in Fig. 5, to a permanent valve stem *u*. The screw thread connection is preferably a loose one and the lower end of valve *t* is somewhat rounded, whereby the valve will center in the outlet even though the 20 stem or crucible becomes warped by heat. The stem and valve are preferably hollowed out to receive a thermometer, conventionally illustrated at *v*. The stem *u* is adjustably connected, as by screw threads, to a yoke *w*, 25 which, as will appear, is vertically reciprocable at properly timed intervals to open and close valve *t*. A hand wheel *x* is provided on the upper end of stem *u* to permit it to be manually turned. The threading of 30 stem *u* into yoke *w* is important, not only for adjusting valve *t* to insure that it engages its seat with the proper pressure, but also for the reason that it facilitates removal and replacement of the valve *t*. Thus, the upper 35 end of the latter is squared, as at *y*, to receive a wrench which may be inserted through the filling opening when plug *s* is removed, to hold the valve against rotation while stem *u* is turned by the hand wheel *x* 40 to disconnect it from the valve. The latter may then be removed from the crucible through the filling opening and a new valve similarly inserted and thereafter connected in an analogous manner to stem *u*.
- 45 The valve *t* is reciprocated by fluid pressure means. Thus, the yoke *w* described is connected to a similar yoke *z* by a pair of rods 25 and the yoke *z* is connected to the piston rod of a cylinder 26 which is supported on bed *A* and between side frames *B*, as shown in Fig. 2. Both yokes extend laterally a sufficient distance to clear the furnace and the rods 25 are movable through, and guided by, suitable openings in frames 50 *B*, bridge *C*, and cover *g*. The cylinder 26 is not shown in detail for there are a number of similar cylinders in the machine for operating various mechanisms by fluid pressure means, and later a single cylinder, 55 typical of all, will be fully disclosed. For the present, it will suffice to state that the cylinder 26 is of the double-acting type in which fluid, as air for example, may be admitted to either side of the piston therein 60 and exhausted from the other side, whereby 65 the valve *t* may be lifted or lowered, as desired.
- The means whereby the molds may be lifted to and clamped against the nozzle *m* will next be described with particular reference to Figs. 2, 17 and 18. Such means consists primarily of two lifting bars 27 which lie within the channels *c* described, and normally rest upon the lower flanges *b*. The bars 27 are simply long rectangular bars of 70 a thickness equal to the depth of channel *c* and of a height somewhat less than that of the channels. The bars 27 are movable vertically and their limits of movement are defined by the flanges *a* and *b*. To each bar 27 75 are secured two rods 28 which extend vertically downward through the flanges *b* and through additional guiding means, such as the lugs 29, toward the base plate *A*. The engagement of rods 28 in holes in the flanges 80 *b* prevents the lifting bars 27 from longitudinal movement in channels *c*.
- The lower end of each rod 28 rests upon a suitable roll which is mounted in the free end of a lever 30. A rock shaft 31 is suitably 85 mounted in each side frame *B* near the base thereof and to each shaft 31 two of the levers 30 are fixed. Also fixed on each rock shaft 31, and intermediate the levers 30 thereon, is a lever 32 (Figs. 1 and 18). The latter carries at its free end a suitable roll which extends into the notch of a jaw 33. The two jaws 33 are formed on opposite ends of a yoke 34 which is centrally attached to the piston rod of a cylinder 35 fixed to base *A* in 90 a manner clearly indicated in Figs. 2 and 18. Guides 35' prevent yoke 34 from turning. It will be obvious that upon the admission of fluid beneath the piston of cylinder 35 that the bar 27 will be lifted and vice 95 versa. It is to be particularly noted, however, that the force exerted on the piston rod of cylinder 35 is multiplied, when transmitted to levers 32, and that the force exerted on the latter is multiplied, when transmitted 100 by the levers 30 to rods 28. Thus, the lifting bars 27, although movable throughout a relatively small range, may be raised by powerful means to clamp the molds against nozzle *m* with adequate pressure.
- 105 The lifting bars are provided with longitudinal channels 36 to receive rolls 37 of a mold supporting bed 38. To opposite sides of bed 38 are attached upstanding and parallel side members 39 between which the mold, 110 to be later described, is received. Such members 39 have flanged upper portions to closely overlie the top flanges *a* of side frames *B* and lower portions which depend between the frames *B* and bed 38 and lie closely adjacent to the lifting bars 27. It is in such depending portions of the members 39 that the described rolls 37 are mounted. Above each roll 37 is a similar roll 40. The rolls 40 ride 115 upon the top surface of the lifting bars 27,
- 120
- 125
- 130

two on each, and the rolls 37 ride upon the upper walls of the channels 36, thus effectually holding the mold carrying bed to lifting bars 27 against relative vertical movement and yet permitting a relative horizontal movement.

Such movement of bed 38 is accomplished by fluid pressure means. Thus, on the outer side of each side frame B and near the top thereof, there is fixed a cylinder 41, arranged with its axis horizontally disposed. The piston rod 42 of each cylinder carries at its free end a bracket 43, the lower end of which slides in, and is guided by ways 44 formed in outwardly extending shelf-like portions of frame B (Figs. 17 and 18). The upper portion of bracket 43 has a vertical slot 45 (Fig. 1) into which the free end of a horizontal rod 46, fixed at its other end in a side member 39, extends. The pin 46 and slot 45 permit the bed 38 to be lifted without interfering with the horizontal movement of the bed. The two cylinders 41 are, of course, connected for simultaneous operation (Fig. 16) and are capable of moving bed 38 to and fro beneath the nozzle m.

The bed 38 is not liftable except when brought into proper position beneath the nozzle. At all other positions of the bed, the engagement of the upper set of rolls 40 with the undersides of flanges a prevent vertical movement of the lifting bars. However, when the mold is properly positioned beneath the nozzle m, the rolls 40 are brought in line with notches 47 (Figs. 2 and 7) in flanges a which notches permit passage of such rolls and thus lifting of bars 27 and the mold-carrying bed supported thereby. The positioning of bed 38 for the above operation may be controlled in any suitable way, as for example, by the abutment of the pistons on rods 42 with the heads of cylinders 41.

Various devices are provided on the mold-carrying bed 38 for moving the mold parts to separate them after the casting operation and to close them after the casting has been extracted and subsequent to the pouring operation. In general, these same, or analogous, devices may be also used for the extraction and insertion of cores, and the term "mold parts" or "mold sections" is to be understood to cover either cores or strict mold parts, such as cope, drag and jaws. The devices referred to are of two general types, viz, those actuated by fluid pressure means, and those actuated mechanically as by cams or the like.

To illustrate the first-named type, there has been shown on the mold-carrying bed 38 a single cylinder 50. Obviously, other similar cylinders may be provided, as many as are necessary for the particular kind of work to be performed. However, to make each cylinder as useful as possible under va-

rious conditions, and particularly to permit the one cylinder to be used for moving mold parts proper, as the cope and so forth, or for pulling heavy cores, the cylinder is so constructed that it may be readily reversed. Thus, the closed end and the piston rod receiving end of cylinder 50 are made of such size that either will fit within a vertical hole 51 in bed 38 and intermediate such end is a flange 52, somewhat larger in diameter, which is adapted to be secured, as by bolting, to the lower face of bed 38. Cylinder 50 is of the double-acting type and fluid, such as compressed air for example, may be admitted to and exhausted from each end of the cylinder by means later to be described.

As shown in Figs. 2, 16, 20 and 21, the piston rod 53 for cylinder 50 extends downwardly, and, when so arranged, carries at its lower end a yoke 54 which extends laterally from both sides of the rod 53 a sufficient distance to clear cylinder 50. Rods 55 secured to the ends of yoke 54 extend upwardly through the bed 38 and such rods are utilized for the actuation of the mold parts. The rods 55 may, of course, be connected in any desired way to any part which requires to be moved. They may be used for moving cores or various parts of the mold proper. As an illustrative example of one way in which the rods 55 may be used, reference is made to Figs. 20 and 21. Here, the upper ends of rods 55 are connected together by a yoke 56, intermediate the ends of which is secured the cope 57 of the mold M. Thus, on admission of fluid to the lower end of cylinder 50, the cope 57 will be lifted, as shown in Fig. 21, to permit extraction of the casting X. In this connection, the abutment of a collar 58 on rod 53 with the lower end of cylinder 50 functions as a stop to arrest the lifting of the cope 57 in the desired position.

Generally, when the cylinder 50 is reversed from the position just described, the yoke 54 will not be found necessary and may be omitted. Particularly, when the cylinder 50 is utilized for pulling heavy cores downwardly, the yoke is unnecessary for the rod 53 can then be directly connected to the core, as that shown at Y in Fig. 18. Here again, a positive stop for the core Y is provided, for, when in extracted position, it abuts the top of cylinder 50 and, when in inserted position, the flange 58' on the core abuts a shoulder 59 provided on the jaws J of the mold.

The mechanically-operated devices on bed 38 will next be described. These devices depend for their actuation on cams, which, in this instance, are stationary, the followers being carried by the movable bed 38. As shown, the cams consist of rectangular bars 60 (Fig. 2) which may be bent up in various forms to secure the desired degree of throw

and to control the relative time of actuation and the rapidity thereof. Since various conditions are encountered and it is unlikely that one style of cam bar 60 will meet all 5 conditions, the cam bars are mounted for convenient removal. The cam bars are also mounted for adjustment and both these results are effected in the following manner. Corresponding ends of the two lifting bars 10 27 are connected together by a cross-bar 61 (Figs. 2 and 7), which has, adjacent each lifting bar, a slotted depending member 62. Preferably, at least, two vertical slots are provided in each member 62, whereby four 15 cam bars may be supported, two along each edge of bed 38. The members 62 are each provided with a series of vertically spaced horizontal holes 63 and each cam bar has at each end a hole for registration with any 20 of the holes 63. The cam bars are held in the slots of members 62 by passing pins 64 through the holes 63 and the registering holes in the cam bars. Thus, the cam bars are readily removed and replaced. They 25 may also be raised and lowered for adjustment. An important feature of the mounting of the cam bars is that they are carried by the lifting bars 27. Thus, they do not move longitudinally with the bed 38, but 30 they do move vertically with bed 38 so that the vertical lift of the latter does not cause an actuation of the cam followers to be described and the possible opening of the mold or the pulling of a core at the time when the 35 mold is clamped against the nozzle of the crucible for pouring.

The cam followers consist of blocks 65 (Fig. 19) each having a slot 66 therethrough and upper and lower rolls 67 mounted to 40 turn in each slot. Each pair of rolls 67 is so spaced as to closely receive between them a cam bar 60, the upper and lower rolls 67 riding on the upper and lower edges of the cam bar 60. Thus, the motion of the cam follower is positive in both directions. The 45 part connected to the cam follower block 65 may be made to suit the purposes in hand. Such part may be a plain rod, as shown at 68 in Figs. 2 and 19. The upper ends of 50 such rods may be connected, similarly to the described rods 55, to move a mold part or a core. The part, referred to, may also consist of a rack, as shown at 69 in Fig. 18. In either case the racks 69 or rods 68 pass 55 vertically upwards through suitable holes provided in bed 38, or more strictly through the side members 39. Although such holes afford guides for the cam followers, it is preferred to provide additional guides 60 which will positively hold the rods and racks against turning. To this end, the bed 38 is provided with pairs of depending guides 70 (Figs. 2, 18 and 21), one pair for each cam follower. Generally, it is desirable to 65 provide for two cam followers on each cam

bar 60, although, if only one is necessary, the other may readily be omitted. Therefore, one pair of guides is provided at each end of bed 38 for each cam bar. Each guide 70 is slotted, as at 71, (Figs. 18 and 21) to 70 receive the cam bar.

For vertical motion, the plain rods 68 may be used and directly connected to the part to be moved. When motion in another direction, as horizontal, is required, the racks 75 69 are used and devices are provided to convert the vertical movement of the racks into movement in the desired direction. The racks 69 generally pass upwardly completely through the side members 39 and the plain 80 rods 68 between such members and the mold, although obviously they may be otherwise arranged. The members 39 are accordingly each provided with two longitudinally spaced holes 72 for the reception of racks 85 69 and the bed 38 with two longitudinally spaced holes 73 on each side for the reception of the plain rods (Fig. 7). The members 39 are each provided with a through, longitudinally disposed, horizontal hole for 90 the reception of one or more pinions 74, the outer ends of which are preferably squared, as indicated, for the reception of a wrench whereby the pinions may be manually turned. 95

When only a single rack 69 is required, only one pinion 74 is employed, and this one may extend from end to end of its member 39 as shown in Fig. 20. Frequently, two independent horizontal motions are necessary on each side of the mold, as with the mold shown in Figs. 17 and 18, wherein the jaws J must be spread and the cores K extracted. Good practice requires that cores K be extracted at a different time than that when jaws J are opened. Consequently, two independent devices are necessary and in such cases, two racks 69 are used and two pinions are provided in the same hole in member 39, as clearly indicated in Fig. 17. 105 Thus, the lower rack 69 meshes merely with the lower short pinion 74 while the upper rack 69 meshes with a considerably longer pinion 74. Provision is made for the reception of three horizontal racks 75 in each member 39. Thus, the upper two racks 75, shown in Fig. 17, may mesh with the long pinion 74 while the other meshes with the short pinion. This allows the lower rack 110 75 to be used for moving cores K while the upper two racks 75 are connected together and to jaws J by a bar 76. When two racks 69 are used on each side of bed 38, two cam bars 60 are generally required and, since 115 these necessarily lie in different vertical planes, while the two racks lie in the same vertical plane, the follower 65 may have a lug 76' formed on its side (Figs. 18 and 19) which permits the rack to be offset into the 120 plane of holes 72. 125

With the mold shown in Figs. 17 and 18, the two cores K may be moved simultaneously and the two jaws J may be moved simultaneously. It sometimes happens that the two cores should be pulled at different times and this can readily be cared for by using different cam bars on each side of the machine. Thus, with the mold shown in Figs. 20 and 21, the large core L is pulled first by one rack 75 while the other is pulled at a later time by the opposite rack 75, each rack being operated by an independent cam bar 60.

Various other combinations may be obtained and many other examples of the use of the fluid-operated and mechanically-operated devices for the movement of mold parts (whether cores or mold parts in the strict sense, as cope, jaws and so forth) might be given, but the two examples described will serve to illustrate the flexibility of the machine within wide limits to meet varying conditions.

In connection with the core pulling devices, whether operated by mechanical or fluid pressure means, I provide means for positively positioning the cores in the desired position in the mold. This feature has been pointed out in connection with the core Y of the mold shown in Fig. 18, but it should be noted that the cores K and N are positioned in the mold by abutment of their racks 75 with the outer face of their molds while with the core L a flange 77 is provided for a like purpose. The feature of positioning the cores accurately in their molds is, of course, most important where the cores are operated by fluid pressure means.

The choice of which of the two described core-operating means are used will depend on the conditions of each case. With large cores, which are rather difficult to pull, the fluid pressure means will generally be employed, due sometimes to the greater power available and sometimes to the character of the core, which may be such as to especially require the yielding character of pull and the variable stroke, not available with the mechanically-operated means. The time when the core is to be pulled will frequently control the choice of the core pulling means. The mechanically-operated means must effect the pulling of the core during the travel of the bed from mold-filling position to the position where the cast articles are extracted. If it is not feasible to pull the core during this interval, the fluid pressure-operated means will be chosen for they operate at any time desired and independently of the movement of the mold-carrying bed.

Shields are provided at both ends of the mold-carrying bed when it is in position for the emission of metal from the nozzle m.

One shield (the rear one as shown in Fig.

2) is of the swinging type and consists of a suitably shaped flat sheet 78 which is pivoted at 79 to lugs on the described frame E. Shield 78 is movable from the full line to the dotted line positions shown in Fig. 2. Movement of shield 78 is effected by abutment with the mold carrying bed 38 when the latter moves to position the mold beneath the nozzle m. When the bed 38 moves back toward the illustrated position, the shield 78 drops by gravity until it is arrested by abutment with the cross-bar described. The latter causes the shield to come to rest in such position that the upper end of a trough 80 thereon is brought in under the nozzle m to catch any drippings of metal therefrom. The trough 80 is secured to shield 78 in downwardly inclined position and has an outlet 81 at one side of the machine (and yet inside of frame B) from which the drippings fall into a suitable receptacle, such as a crucible (not shown) which may be placed on bed A. The trough 80 also affords a convenient means of emptying the crucible h.

The front shield is of the reciprocating type and lifts vertically although it is preferably also pivoted for reasons to appear. The front shield is shown at 82 in Figs. 1 and 2, and as shown, has flanges 83, preferably curved as shown, on all four sides. The shield 82 is pivoted at 84 at its upper corners to the upper ends of two laterally spaced rods 85 which extend vertically downward and are slidably mounted in frames B. Cylinders 86 are also suitably supported on the side frames B with their piston rods 86' depending therefrom (Fig. 1). The lower end of each piston rod is connected to the lower end of the adjacent rod 85 by a bar 85'. The shield 82 is normally held in lifted position, as shown, but is arranged to be lowered after the mold has been moved in under nozzle m for the pouring operation. The use of the flanges 83 is important as preventing any metal thrown against the shield 82 from spitting out along the edges of the shield as would occur if the shield were flat and the flanges omitted. With the curved flanges, metal striking the shield shoots therealong until it strikes the curved flanges which direct it inwardly away from the operator. The use of a shield reciprocable in a straight line path is important as eliminating the powerful fan effect incident to the use of a swinging shield. No powerful gusts of air are thrown into the face of the operator when the shield 82 moves up or down. The advantages of the swinging shield are, however, retained by pivoting it to its operating rods 85. Thus, the shield can be manually drawn back even when lowered to permit the operator to take a last peep at the mold, when necessary. Also the shield is yieldable if obstructions are encountered. For example,

should bed 38 move backwardly into the illustrated position before shield 82 was completely out of the way, the shield would be swung on its pivots and clear itself of the bed without breaking.

The various cylinders 26, 35, 41, 50 and 86 may be constructed in any suitable manner and the invention is independent of the particular cylinder construction adopted.

10 As typifying one suitable construction for the cylinders, their pistons, packing, and so forth, reference is made to Fig. 13, wherein the internal construction of one cylinder, which may be considered as cylinder 26, is shown. Such cylinder is of the double-acting type and has passages 87 and 88 leading to each end thereof. With the single acting cylinder one of such passages would of course, be omitted. The one passage for 20 each end of the cylinder serves as both inlet and exhaust although separate inlet and exhaust passages may be provided, if desired. The piston 89 is of not unusual form and is suitably secured to a piston rod 90, which 25 passes outwardly through a removable head 91. Instead of the usual stuffing box located outside head 91, the cylinder 26 is counter-bored to receive a disk 92 and a packing 93 is applied between such disk and head 91, 30 the several members being clamped together by the cap screws 94 which hold the head to the cylinder. The packing 93 also extends downwardly between disk 92 and piston rod 90.

35 The admission and exhaustion of fluid to and from the described cylinders is controlled by a series of valves which are automatically closable, but are opened by cams, which are all driven from a common source 40 of power to coordinate the various operations of the machine.

As indicated in Figs. 1, 16 and 18, the valves are arranged in two groups,—one, the inlet group, being arranged on one side of the 45 machine, and the other, the exhaust group, being located on the other side of the machine. Also the inlet valve for each cylinder is located directly opposite the exhaust valve for the same cylinder. The arrangements described however, are not necessarily 50 essential and may be varied, as will be later pointed out, and are mentioned only because they simplify the description and particularly the piping diagram shown in Fig. 16.

55 Referring to this figure, the several inlet valves are indicated conventionally at 95, 96, 97, 98, 99, 100, 101 and 102. All are served from a common manifold 103, to which a suitable fluid, as air, under pressure 60 is supplied. The corresponding exhaust valves are indicated conventionally at 104, 105, 106, 107, 108, 109, 110, and 111. The valves 95 and 104 are connected by pipes 112 and 113 respectively, to one end of cylinder 50 and the other end thereof is con-

nected by pipes 114 and 115 to valves 100 and 109, respectively. When the cylinder 50 is connected, as shown in Fig. 21, the valve 95 controls the lifting, and the valve 100 the lowering, of the cope. The valve 70 96 is connected to the lower end of cylinder 35 by a pipe 116 and thus controls the lifting of the mold and the clamping of the same to the nozzle of the crucible. The lowering of the mold is accomplished by 75 gravity under the control of the exhaust valve 105 which is connected to the lower end of cylinder 35 by a pipe 117. The cylinders 86 are connected together at their lower ends and to the inlet manifold 103 by 80 pipes 118, whereby constant pressure is provided to hold rods 85 normally in raised position so that the shield 82 is maintained in lifted position. The upper ends of these cylinders are connected together, and also 85 connected to pipe 116, by pipes 119, whereby the admission of fluid under pressure to the upper end of cylinders 86 is controlled by the valve 96 and the exhaustion of such fluid by the valve 105. Thus, the shield 90 95 96 lowers when the lifting bars 27 are raised and raises when such bars are lowered. The area of the lower faces of the pistons in cylinders 86 is less than that of the upper faces due to the subtraction of the areas of 95 the piston rods 86'. Thus, upon the opening of valve 96, fluid under the same unit pressure acts on both faces of each piston but the total pressure on the upper face is greater than that on the lower face so that 100 the pistons move downwardly. The valves 97 and 106 are connected together by a pipe 121 which is also connected to the forward end of each cylinder 41. The opposite end of each of the latter is connected 105 to a pipe 122 which also connects the valves 102 and 111 together. Thus, the valve 97 controls the movement of the bed 38 into mold-filling position and the valve 102 the return movement of bed 38. The valves 98 110 and 99 control the opening of the valve 7 in the crucible and are connected by pipes 123 and 124, respectively, to opposite ends of the cylinder 26. Opposite ends of the latter are also connected by pipes 125 and 126 to the exhaust valves 107 and 108, respectively. The valve 101 controls the admission of air to the crucible 7 to place the metal under pressure. Accordingly, it is connected to the described pipe *q* and the pipe *r* is connected to the exhaust valve 110. 115 Each of the valves described is of similar construction and one only need therefore be described. Referring to Figs. 10, 11, and 12, the inlet valve 97, which is typical of all, consists of a generally rectangular body, suitably secured to frame B, and is formed with inlet and exit chambers 127 and 128, respectively. The chamber 127 is connected to the inlet manifold 103 by a pipe 129 and, 120 125 126 127 128 129 130

preferably, a manually operable valve 130 is interposed therein to shut off or regulate the admission of fluid to chamber 127. A valve disk 132, having a stem 133 slidably mounted in the valve body, normally prevents communication between the chambers 127 and 128 but when disk 132 is moved downwardly communication is established by means of recesses 131. The valve body 10 is recessed at its upper end to receive a rectangular block 134 which is fixed to stem 133 and a spring 135, acting between the block and body normally holds disk 132 in closed position. Suitable packing is provided for stem 133, as indicated at 136, the spring 135 serving to compress such packing about stem 133 through the intermediary of a gland 137. The block 134 carries a roll 138 for engagement with the periphery of a cam 139 fixed on a shaft 140 which is suitably mounted on frame B and extends from end to end thereof, overlying all of the described inlet valves. Each of these valves has a separate cam on the shaft 140, as 25 clearly indicated in Fig. 1. A similar shaft 141 overlies all the exhaust valves, as clearly indicated in Fig. 18 and it is to be understood that on shaft 141 there is a separate cam for each valve, as indicated by the cam 142 for valve 105 in Fig. 18. The two shafts 140 and 141 are driven by bevel gearing, as indicated in Figs. 1 and 7, from a common drive shaft 143, which is suitably mounted in and extends between the side frames B 30 and is driven in a manner to be described.

Each of the described cams, as 139, has a smooth finished periphery, which is of such diameter that when the roll, as 138, rides upon it the valve disk, as 132, is in open position, and also has a cut-away portion, as 144 (Fig. 10), which will permit the valve disk to seat itself. Each cam, whether inlet or exhaust, is suitably contoured to effect the opening and closing 45 of its valve at the desired time and to maintain the valve opened or closed for the desired intervals to coordinate the various automatic operations so that they occur in the proper timed relation to be described.

It has been pointed out that it is not necessary to arrange the inlet and exhaust valves in the manner described. Since the shafts 140 and 141 turn in unison, they are, in practical effect, the equivalent of one shaft and any valve may be arranged at any desired point on either shaft. As a matter of fact, each pair of inlet and exhaust valves may be combined and considerable piping eliminated thereby.

The modification just referred to is shown in Figs. 14 and 15 and will now be described. The valve there shown may be considered as taking the place of the valves 99 and 108, which control the lowering of the metal valve *t*. Such valve comprises

a single body 145, which, instead of being fastened directly to frame B, is secured to an intake manifold 146, which in turn is secured to frame B. Mounted to slide vertically in the body 145 are two spaced valve stems 147 and 148 and between these stems is an oscillatable plug valve 149 which is provided with a handle 150, whereby it may be manually turned. Valve 149 has a lateral passage 151 therethrough, which, when the valve is positioned as shown, registers with, and connects, two passages 152 and 153 provided in the body. The passage 152 is connected directly to manifold 146 by a passage 154. The passage 153 communicates at all times with an admission chamber 155 in the body, such chamber having an annular exit 156 around the stem 147 and being closable by an inlet valve 157 thereon. An exit chamber 158 is provided in the body below an exhaust valve 159 and such chamber at all times communicates with the annular exit 156 by means of a passage 160. A passage 161 leads from the exit chamber 158 to a single pipe, as 162, which in this instance leads to the upper end of cylinder 26. The exhaust valve 159 normally closes off communication between the chamber 158 and an annular passage 163, which at all times communicates with a chamber 164. From the latter, a passage 165 leads to a recess 166 in body 145 and thus to the atmosphere.

The valves 157 and 158 are mounted in a manner similar to that described and are 100 yieldingly held in closed position. The valves 157 and 159 are also opened by cams, as 167 and 168 respectively, on one of the cam shafts, as 140. Instead of directly operating the valves from their cams, an intermediate element, a rocker arm 169, is provided, which is pivoted at one end and rests at its outer end on the top of the valve stem, and carries a roll 170 for engagement with the cam. Each rocker arm, as 169, has a plug 171 on its outer end to receive the socket of a suitable lever, whereby the operator may manually open any of the valves, if desired, independently of the automatic mechanism.

The automatic mechanism for driving the shaft 143, together with the controlling devices for such mechanism, will next be described with particular reference to Figs. 2 and 9. The source of power may be chosen as desired, but, for illustrative purposes, will be considered as an electric motor 173, which is suitably supported from bed A and underlies the frames F and G, already described. The frame G supports a longitudinally disposed shaft 174 and one end of this shaft is connected to motor 173 by gears 175, the ratio of the gears being such as to drive shaft 174 at a much slower speed than that of the motor. Upon such end of shaft 174,

there is mounted for free rotation thereon a gear 176 and fixed thereto is a clutch element 177, adapted to engage with a mating clutch element 178, which is slidably keyed 5 to shaft 174, whereby gear 176 may be driven from the latter. The frame F likewise supports a drive shaft 179 which parallels and directly overlies shaft 174. On shaft 179, and mounted for free rotation, is a gear 180 which meshes with gear 176. Gear 180 has fixed thereto a clutch element 181 which is adapted to mesh with a mating element 182 slidably keyed to shaft 179, whereby the latter may be driven from shaft 174, but 15 preferably at reduced speed. The shaft 179 has fixed thereto a worm 183, which meshes with, and drives, a worm gear 184 fixed on the described shaft 143. It will thus be seen that the cam shafts 140 and 141 may be 20 driven continuously by the motor 173 when both sets of clutch elements 177, 178, and 181, 182 are engaged, although at considerably reduced speed.

It will be also seen that the machine may 25 be disconnected from its source of power in two places. One clutch, comprising the elements 177 and 178, is used particularly for starting and stopping the machine manually, as in emergencies. The other clutch, 30 comprising the elements 181 and 182, is used for automatically stopping the machine at the end of each complete cycle of operation and stops the machine always at a predetermined point in the cycle. Provision 35 is made for manually preventing the automatic stopping of the machine, however, so that a series of successive cycles may be accomplished without interruption, when desired.

40 The controlling mechanism for the automatic clutch 181, 182 will first be described.

The clutch element 182 is circumferentially grooved to receive the forked end of a clutch shifter 185, the other end of which is fixed 45 to a rod 186. The latter is slidably mounted in frame F for reciprocation in a direction parallel to shaft 179 and is normally held in the illustrated position by a spring 187 to disengage elements 181 and 182. Mounted transversely in the frame G is fixed an upstanding lever 189 adapted to abut the inner end of rod 185 and cause the engagement of elements 181 and 182. Fixed on the outer end of shaft 188 is an upstanding lever 190 upon the end of which is a roll 50 (Figs. 2 and 7) to engage the periphery of a master cam 191 fixed on shaft 143. This cam 191 is merely a circular disk which has a single recess in its periphery to receive the roll on lever 190 and permit the latter to be moved to such position that the clutch elements 181 and 182 are disengaged. At all other points, in its periphery, the cam 55 holds lever 190 in such position that the clutch elements 181 and 182 are engaged.

To manually engage the clutch elements and thereby release the machine for automatic operation after it has been stopped by cam 191, a link 192 is connected to lever 190 intermediate its ends and extends forwardly 70 of the machine for connection to the upper end of a lever 193 (Fig. 2).

The other clutch, 177, 178, is similarly grooved to receive the forked end of a clutch shifter 194 (Figs. 2 and 8), which is fixed to a rod 195, slidably mounted in frame G and normally held in retracted position by a spring 196. Mounted in frame F above the described cross shaft 188 is a similar shaft 197, to which is fixed a depending 80 lever 198. The lower end of lever 198 engages the inner end of rod 195 to slide the latter against the force of spring 196. On the outer end of shaft 197 is a lever 199 and a link 200 (Fig. 8) connects this lever 85 to a second lever, similar to lever 193, but fixed to the pivot 201 (Fig. 1). On this same pivot, a second lever 202 is fixed which is located outside the adjacent side frame B in a position for convenient access. Lever 90 202 carries a pivoted latch arm 203 which, when lever 202 is moved forwardly (to the left) from the position shown in Fig. 1, will catch against the shoulder 204 on frame B and hold lever 202 in such position that the clutch elements 177 and 178 are engaged. By lifting latch 203 to free it from shoulder 204, the lever 202 will be released and the clutch elements 177 and 178 again engaged.

Connections have been described for manually engaging the clutch 181 and 182 after 100 they have been disengaged by the operation of the master cam 191. These connections were traced to a lever 193 shown in Fig. 2. It is to be understood that the lever 193 105 is fixed to a pivot 205 and that on the outer end of this pivot there is a suitable operating lever, like the lever 202, which may be latched in position in a similar manner to hold the elements 181 and 182 engaged. 110 When such operating lever is not latched, the machine automatically stops at the end of one revolution of the cam shafts 140 and 141 and thus after the completion of one cycle of operation. If several successive 115 cycles of operation are desired, the operating lever is latched, but where the machine is operated with intervals between successive cycles, such lever is not latched. The lever then is merely used to hold the clutch 120 elements 181 and 182 engaged until the cam 184 can come into play to hold them.

The lever 202 is used when it is desired to stop the machine at any other point than at the end of a cycle of operation. It is 125 also used in emergencies and at all other times when the automatic stop is not capable of fulfilling the desired requirements.

Preferably, and as a desirable adjunct of the machine, I provide means for auto- 130

matically cleaning the nozzle m on each cycle of operation of the machine and prior to the clamping of the mold thereagainst. Although considerable pressure is available 5 to clamp the mold against the nozzle and a sufficient seal thereby afforded, the presence of particles of foreign material on the nozzle will at least make the mold "spit" which is undesired. General practice requires that 10 the operator manually wipe the nozzle before the mold is clamped against it.

Referring to Fig. 23; a relatively thin scraping or wiping blade 210 is mounted for reciprocation in suitable guides on the 15 bottom of casing D. Springs 211 normally hold such blade in the illustrated position wherein it abuts a stop 212. An upstanding pin 213 secured to bed 38 (Figs. 2 and 7) is arranged to engage the rear end of blade 210, as indicated in Fig. 23, and to move it 20 sufficiently to carry the forward, slightly upturned edge across the face of nozzle m to clean it. The blade 210 moves a sufficient distance to bring a hole 214 therein in concentrical relation with the nozzle so that 25 the upper end of the mold may pass through hole 214 and be clamped against the nozzle.

Preferably, also, means are provided for automatically cleaning the mold after the 30 casting has been extracted. Thus, as indicated in Figs. 2 and 21, a perforated pipe 216 is arranged on each side wall 39 of the mold carrying bed. The pipes 216 are so located that jets of fluid under pressure 35 emitted therefrom may impinge on and clean the interior surfaces of the mold sections, as best shown in Fig. 21. It will readily be apparent that these jets of fluid may be also utilized for the purpose of cooling the molds.

40 For controlling the operation of the mold cleaning means, a self closing valve (Fig. 22) is provided in the front cross bar 61. Thus, an inlet chamber 217 is provided which is connected by a pipe 218 to a suitable 45 source of fluid under pressure, as for example, the manifold 103. An exit chamber 219 is also provided which connects by a flexible pipe 220 with the pipes 216. A valve 221 normally closes off communication 50 between the chambers 217 and 219 by reason of a spring 222 acting against a collar 223 on the stem 224 of the valve. Stem 224 is arranged to be engaged by the bed 38 (Fig. 2), as the latter comes to rest in the illustrated 55 position, and moved to open valve 221, whereby the jets of fluid under pressure are emitted to clean the mold sections during the interval of rest of the carrier in its outer position.

60 The operation of the machine will now be described. Assuming that a mold like that shown in Figs. 20 and 21 is provided on bed A and that the casting X has been extracted, the operator would start the machine by 65 pulling forwardly the operating lever on

shaft 205, it being assumed that the other lever 202 has already been latched in its forward position. The clutch 181, 182 is held closed until the end of the cycle, by the cam 191. The machine having been 70 started, the various operations are all accomplished automatically.

First, the bed 38 will be carried inwardly by the cylinders 41, which are supplied with fluid under pressure by the opening of valve 75 97, the exhaust valve 106 being closed and the exhaust valve 111 being open. As the bed approaches the end of its inward stroke, the exhaust valve 106 commences to close and thereby the bed may be gradually brought to rest with a dashpot effect. The same general result may be accomplished in other ways, as for example, by cutting off the fluid admitted to cylinder 41 through valve 97 by closing the latter before the 80 end of the stroke, allowing the fluid to expand, and near the end of the stroke opening of the exhaust valve 106 slightly.

During the inward travel of bed 38, the rack bars 69 are actuated by the cam bars 60 to replace the cores L and N. According to the shape of the cam bars, these two cores may be replaced at substantially the same time or either may be replaced before the other, as desired. The particular results 85 desired in any given case will, of course, vary and the cam bars may be varied to suit the conditions. Before the ends of the inward stroke of bed 38, the cope 57 is replaced, and the time of replacement may 90 vary as desired since it is effected by fluid pressure means. It may occur before or after the replacement cores L and N according to the setting of the cam for valve 100. Valve 100 first opens to admit fluid under 95 pressure to the upper end of cylinder 50 while the exhaust valve 104 is open. A cushioning of the cope as it moves into place against the mold may be obtained by partially closing the exhaust valve 104 as already 100 described. The fluid pressure should however, be maintained in the upper end of cylinder 50 to hold the cope tightly clamped against the mold until after the pouring 105 operation.

The mold parts having been assembled and the bed 38 moved inwardly, all of which operations occur in close sequence, a second series of operations ensue. First, the lifting bars 27 start to rise to clamp the mold against nozzle m . This is accomplished by the cylinder 35 under the control of valve 96, the exhaust valve 105 being closed and valve 96 is arranged to maintain pressure 110 during the pouring operation to hold the mold tightly clamped against the nozzle. As the last described operation takes place, the valve 101 opens to admit fluid in crucible h and remains open until the valve t has 115 been opened for the pouring operation and 120 125 130

then closed, when valve 101 closes and exhaust valve 110 opens. The fluid having been placed under pressure and the mold having been clamped to the nozzle *m*, the 5 valve 98 is opened to cause the lifting of the valve *t*, the exhaust valve 107 being closed and exhaust valve 108 being open. Valve 98 holds valve *t* open for an interval sufficient to permit the mold to fill and then 10 closes while exhaust valve 107 opens. At the same time exhaust valve 108 closes and inlet valve 99 opens to cause the lowering of the valve *t*. As described, no cushioning of the descent of valve *t* is desired but 15 the valve *t* is driven into place with a slam to obtain the desired ram-like effect and an intensification of the pressure on the metal. In this connection the lower cylindrical end 20 of the valve enters the gate opening of the mold to function as a plunger while the valve proper seals the outlet. The action is analogous to driving a cork into a completely filled bottle and a substantial intensification of pressure results. The valve 25 99 also remains open until a subsequent opening of valve 98 to hold the valve *t* tightly in closed position. The forcible closing of valve *t* cannot break or otherwise injure crucible *h* since at the time of closing, 30 the crucible is firmly supported from below by the clamping pressure of the mold on nozzle *m*.

As the bed 38 approached the end of its inward stroke it engaged the tilting shield 78 35 and moved it into the dotted line position shown in Fig. 1 to protect the operator from possible injury due to metal escaping from the rear of the machine. As the bed 38 came to rest in the described position and started 40 to lift toward the crucible *h*, the front shield 82 was lowered, as already described and is held lowered until the valve 96 closes and valve 105 opens. Should the operator wish to take a look at the mold after shield 82 has 45 been lowered, he may do so by manually swinging the shield outwardly on its pivot 84. The mold having been filled with metal, or other fluid, and the valve *t* closed, as described the exhaust valve 105 is opened 50 (valve 96 having previously closed) whereupon the lifting bars 27 descend by gravity as the fluid escapes from cylinder 35 and shield 82 is lifted. Then valve 102 opens to admit fluid to the rear ends of cylinders 41 55 and exhaust valve 106 opens to permit the escape of fluid from the opposite ends of the cylinders. Thus, the bed 38 is carried forwardly and shield 78 drops back to the position shown by full lines to position through 60 80 so as to catch the drip from nozzle *m*. The bed may be brought gradually to rest at the end of its outward stroke by checking the exhaustion of fluid from the opposite end of the cylinder under the control of 65 valve 106. The valve 102 is preferably held

open to maintain the bed 38 in its outer position until time for the bed to start on a succeeding inward stroke.

During the return of bed 38, the cores L and N are extracted by the cam bars 60 and 70 after the extraction of the cores, the cope 56 is lifted. The latter operation is accomplished by the opening of valve 95 and the opening of the exhaust valve 109, the former remaining open for a sufficient interval to 75 permit extraction of the casting X.

Unless the operating lever for the clutch 181, 182 is latched back, as described, the machine comes to rest by the recess in master cam 191 coming into position to receive the 80 roll on lever 190. The machine comes to rest with the bed 38 in its outer position and with the mold parts in separated relation.

The operation of the machine, when a mold, like that shown in Figs. 17 and 18, is 85 used, is substantially the same as that already described. The only differences in operation in any event are due to differences in mold construction, which frequently require different timing of the movement of the 90 mold parts. For example, the large core Y would probably be pulled first and then the cores K extracted and finally the jaws J 95 opened.

Thus, I have provided a casting machine 95 which is characterized by the performance of the several operations automatically in proper sequence and by the utilization of the resultant advantages in clamping pressure independent of stroke and in the yielding effect available for the extraction of cores. The machine is further characterized by its flexible arrangement, the valve actuating cams being changeable to produce the 100 various effects desired, and by the flexible arrangement of devices, both mechanical and fluid pressure, for moving mold parts in various ways and at various times to meet the varying conditions of each mold encountered. 110

The invention has been disclosed herein, in an embodiment at present preferred, for 115 illustrative purposes but the scope of the invention is defined by the appended claims rather than by the foregoing description.

What I claim is:

1. In a casting machine, of the type where-in a mold is clamped against a crucible with its filling opening in communication with the outlet of the crucible, a combined valve and plunger operable to first open said outlet and allow the mold to be filled with the fluid to be cast and subsequently as a plunger to intensify the pressure of the fluid in the 120 mold and finally to close said outlet.

2. In a casting machine, a crucible having a discharge nozzle for the fluid to be cast, a mold carrier, means to move the latter to carry the mold against the nozzle and subse- 125 130

quently remove it therefrom, and a combined plunger and valve cooperating with said nozzle while the mold is held thereagainst to first intensify the pressure of the fluid in the mold and subsequently close the outlet of said nozzle.

3. In a casting machine, of the type where-
in a mold is periodically clamped against a
crucible with its filling opening in communi-
cation with the outlet of the crucible and a
valve controls the opening and closing of
said outlet and operates to close the same
while the fluid in said crucible is placed un-
der pressure, a plunger provided on said
valve operable after the opening thereof to
move in said outlet and intensify the pres-
sure of the fluid in the filled mold.

4. In a casting machine, a crucible having
a discharge nozzle, a valve therefor, auto-
matic means to open and close said valve, a
mold carrier, a mold thereon, automatic
means to move the carrier to and clamp the
mold against said nozzle before the opening
of said valve and to hold the mold thus posi-
tioned until the closing of said valve, pneu-
matic means to place the fluid in said crucible
under pressure prior to the opening of
said valve, and a common driving mecha-
nism to coordinate the operation of all said
automatic means.

5. In a casting machine, a crucible having
a discharge nozzle for the fluid to be cast, a
mold carrier, means to move the latter to
carry the mold against the nozzle and subse-
quently remove it therefrom, a combined
plunger and valve cooperating with said
nozzle while the mold is held thereagainst to
first intensify the pressure of the fluid in
the mold and subsequently close the outlet
of said nozzle, and automatic means for
placing the fluid in said crucible under pres-
sure prior to the opening of said valve.

6. In a casting machine, a crucible for the
fluid to be cast having an outlet opening pro-
vided with a valve seat, a valve cooperating
with said seat to open and close said outlet
opening, a passage provided in said crucible
beyond said valve seat, and an extension pro-
vided on said valve to operate as a plunger
in said passage.

7. In a casting machine, a crucible having
a discharge nozzle for the fluid to be cast, a
valve therefor, a mold carrier movable to
and from the nozzle, a mold thereon, auto-
matic means to move the carrier in each di-
rection and to clamp the mold against the
nozzle when moved in one direction, auto-
matic means to open and close said valve,
pneumatic means to place the fluid in said
crucible under pressure prior to the opening
of said valve, and a common driving mecha-
nism for all said automatic means to coordi-
nate the movement of the mold carrier and
valve.

8. In a casting machine, a crucible having

a discharge nozzle for the fluid to be cast, a
valve therefor, a mold carrier movable to
and from the nozzle, a mold on the carrier
having separable sections, automatic means
to move the carrier in each direction and
clamp the mold against said nozzle when
moved in one direction, automatic means to
separate the mold sections after the mold is
disengaged from the nozzle and to clamp
such sections together before the mold is
again engaged with the nozzle, automatic
means to open and close said valve, pneu-
matic means to place the fluid in said cruci-
ble under pressure prior to the opening of
said valve, and a common driving mecha-
nism for all said automatic means to coor-
dinate the movement of the mold carrier
and valve.

9. In a casting machine, a crucible having
a discharge nozzle for the fluid to be cast, a
valve therefor, a mold carrier, means oper-
able by fluid pressure to move the carrier to
and from the nozzle, a mold on the carrier
having separable sections, cores associated
with said molds, means operable by fluid
pressure to separate said sections and ex-
tract said cores after the carrier moves away
from said nozzle and to clamp the sections
together and insert said cores before the
carrier moves under said nozzle, valves to
control the operation of each of said fluid
pressure means, pneumatic means to place
the fluid in said crucible under pressure
prior to the opening of the first-named valve,
and driving mechanism to operate the last-
named valves in proper timed relation.

10. In a casting machine, a crucible hav-
ing a discharge nozzle, a valve therefor,
means operable by fluid pressure to open and
close said valve, a mold carrier, a mold there-
on, means operable by fluid pressure to move
the carrier to and clamp the mold against
said nozzle before the opening of said valve
and to hold the mold thus positioned until
the closing of said valve, means including a
control valve to place the fluid in said cruci-
ble under pressure prior to the opening of
the first-named valve, valves to control the
operation of each fluid-pressure means, and
driving mechanism to operate the control
valve and last-named valves in proper timed
relation.

11. In a casting machine, a crucible hav-
ing a discharge nozzle, a mold carrier, means
operable by fluid pressure to move the latter
beneath said nozzle and to later effect a re-
turn movement, a mold on said carrier,
means operable by fluid pressure to lift the
latter at the end of the first-named move-
ment and to lower the carrier before the re-
turn movement, valves to control the opera-
tion of each of said fluid pressure means, and
driving mechanism to operate the last-named
valves in proper timed relation.

12. In a casting machine, a crucible hav-

- ing a discharge nozzle, a mold carrier, means operable by fluid pressure to move the latter beneath said nozzle and to later effect a return movement, a mold on said carrier having separable sections, means operable by fluid pressure to lift the latter at the end of the first-named movement and to lower the carrier before the return movement, means operable by fluid pressure to separate said sections after the carrier has been lowered and to again clamp them together before the carrier is lifted, valves to control the operation of each of said fluid pressure means, and driving mechanism to operate the last-named valves in proper timed relation. 13. In a casting machine, a crucible having a discharge nozzle for the fluid to be cast, a valve therefor, a mold carrier movable to and from the nozzle, a mold on the carrier, means operable by fluid pressure to move the carrier in each direction and to clamp the mold against the nozzle when moved in one direction, means operable by fluid pressure to open and close said valve, means including a control valve to place the fluid in said crucible under pneumatic pressure prior to the opening of the first-named valve, valves to control the operation of each fluid pressure means, and driving mechanism to operate the control valve and last-named valves in proper timed relation. 14. In a casting machine, a crucible having a discharge nozzle for the fluid to be cast, a valve therefor, a mold carrier, a mold on the carrier having separable sections, means operable by fluid pressure to move the carrier in each direction and to clamp the mold against the nozzle when moved in one direction, means operable by fluid pressure to open and close said valve, means operable by fluid pressure to separate the mold sections after the mold is disengaged from the nozzle and to clamp such sections together before the mold is again engaged with the nozzles, means including a control valve to place the fluid in said crucible under pneumatic pressure prior to the opening of the first-named valve, valves to control the operation of each fluid pressure means, and driving mechanism to operate the control valve and last-named valves in proper-timed relation. 15. In a casting machine, a discharge nozzle, a mold carrier, means to move the latter in a straight line toward and away from the nozzle and in a direction substantially transverse to the discharge of fluid therefrom, and means operable at the end of the first and before the second named movement to move the carrier toward the nozzle and subsequently away from the nozzle in a direction parallel to the discharge of fluid from said nozzle. 16. In a casting machine, a discharge nozzle, a mold carrier, means operable by fluid pressure to move the latter toward and away from the nozzle and in a direction substantially transverse to the discharge of fluid therefrom, means operable at the end of the first and before the second named movement to move the carrier toward the nozzle and subsequently away from the nozzle in a direction parallel to the discharge of fluid from said nozzle, and automatically operable devices for controlling said fluid pressure means so that the carrier is gradually brought to rest at the end of each transverse movement. 17. In a casting machine, a discharge nozzle, a mold carrier, means operable by fluid pressure to move the latter toward and away from the nozzle and in a direction at right angles to that of the discharge of fluid therefrom, means operable by fluid pressure at the end of the first and before the second named movement to move the carrier toward the nozzle and subsequently away from the nozzle in a direction parallel to the discharge of fluid from said nozzle, and automatically operable devices for controlling each fluid pressure means and coordinating the movements effected by each. 18. In a casting machine, a discharge nozzle for the fluid to be cast, a mold carrier movable to and from a position beneath the nozzle, fluid pressure means to reciprocate the carrier, fluid pressure means to lift the carrier toward and clamp the mold against said nozzle, valves to control each fluid pressure means, a common driving means, and devices thereon to separately operate each valve, whereby the movements effected by the fluid pressure means may be coordinated. 19. In a casting machine, a discharge nozzle for the fluid to be cast, a reciprocable mold carrier movable to and from a position beneath the nozzle, a mold on the carrier having separable sections, fluid pressure means to separate said sections and to subsequently clamp them together, fluid pressure means to reciprocate the carrier, fluid pressure means to lift the carrier toward and clamp the mold against said nozzle, valves to control each fluid pressure means, a common driving means and devices thereon to separately operate each valve, whereby the movements effected by the fluid pressure means may be coordinated. 20. In a casting machine, a crucible, a mold adapted to be clamped thereagainst with its inlet in line with the outlet of the crucible, a valve to open and close said outlet, and fluid pressure means to forcibly drive said valve into the outlet with a ram-like action to close the latter while the mold is clamped against the crucible. 21. In a casting machine, a crucible, a

15 mold adapted to be clamped thereagainst with its inlet in line with the outlet of the crucible, a valve to open and close said outlet, means actuated by fluid pressure to open said valve while the mold is clamped against said crucible and to subsequently close the valve before the mold is withdrawn, and controlling devices for said fluid pressure means arranged to suddenly 20 close the valve by driving it into said outlet with a ram-like action.

22. In a casting machine, a discharge nozzle for the fluid to be cast, a mold carrier movable toward and away from said nozzle, a mold on the carrier, means automatically operable by fluid pressure to move the carrier toward and clamp the mold against said nozzle, a valve to control said means, mechanism automatically operable to open 25 and close said valve at definite intervals, and means permitting manual operation of said valve when an opening or closing thereof at other intervals is desired.

23. In a casting machine, a nozzle for discharging the fluid to be cast, a mold carrier movable to and from a position to receive the discharge from the nozzle, said mold having movable sections, means carried by the movable carrier and operable 30 by fluid pressure to move one of said mold sections relatively to the other and independently of the movement of the carrier.

24. In a casting machine, a mold carrier, a mold thereon, a core associated with the 35 mold, means actuated by fluid pressure to extract said core from the mold and to subsequently reposition it therein, a valve to control said means, mechanism automatically operable to open and close said 40 valve at definite intervals and means permitting manual operation of said valve when an opening or closing thereof at other intervals is desired.

25. In a casting machine, a mold carrier, a mold thereon, a cylinder mounted in said carrier below the mold a piston and piston rod for the cylinder, a core associated with said mold and connected to said piston rod, and means to regulably admit fluid under 50 pressure to and exhaust it from either end of said cylinder, whereby the core may be gently extracted and reinserted and firmly clamped in position.

26. In a casting machine, a mold carrier, a mold thereon having separable sections and cores, a cylinder mounted in the carrier below the mold and capable of being reversed so that its piston rod may extend upwardly or downwardly as desired, where- 55 by the cylinder presents a flexible means for use in various ways for moving said cores and sections, and means to regulably admit fluid under pressure to and exhaust it from either end of said cylinder.

27. In a casting machine, a discharge nozzle

70 for the fluid to be cast, a mold carrier movable to and from the latter, a mold thereon having laterally and longitudinally movable sections, and means operable during the movement of the carrier to move each of said sections independently of the other.

28. In a casting machine, a discharge nozzle for the fluid to be cast, a mold carrier movable to and from the latter, a mold thereon having laterally and longitudinally 75 movable sections, and means operable during the movement of the carrier to move certain of said sections each independently of the other, and means on the carrier to move other sections independently of the movement of the mold carrier.

29. In a casting machine, a nozzle for the discharge of fluid to be cast, a mold carrier movable toward and away from such nozzle, spaced upstanding side walls for the 80 carrier between which the mold is received, longitudinal openings provided in such side walls for the reception of pinions, one or more pinions rotatable in such openings, a series of vertical openings in each side wall 85 to receive rack bars in position to mesh with a pinion, other openings provided laterally in said side walls to receive other rack bars in position to mesh with a pinion, said rack bars, supporting means below the carrier 90 to receive a series of cam bars, said cam bars, at least one thereof positioned for engagement by one of the first-named rack bars whereby a pinion may be turned directly from such rack bar to laterally move 100 one of the second rack bars during the movement of the carrier.

30. In a casting machine, a nozzle for the discharge of fluid to be cast, a mold carrier movable toward and away from the nozzle, an upstanding side wall on the carrier having a longitudinal opening therein, two pinions independently rotatable therein, a rack bar for and in mesh with each pinion and slideable vertically in said wall, a separate cam bar for each rack bar and arranged to move the latter on movement of the carrier, and a rack bar for and in mesh with each pinion and passing laterally through 110 said wall.

31. In a casting machine, a nozzle for the discharge of fluid to be cast, a mold carrier, spaced rails along which said carrier is reciprocable toward and away from the nozzle, and means operable at the end of the 115 first-named stroke to lift the rails toward and clamp the mold against the nozzle.

32. In a casting machine, a nozzle for the discharge of fluid to be cast, a mold carrier, spaced rails along which said carrier is reciprocable toward and away from the nozzle, means restraining the carrier against lifting movement during its longitudinal movement, and means operable as the carrier comes to rest adjacent the nozzle at the end 120 125 130

of its longitudinal movement in one direction to lift the rails and thus the carrier toward the nozzle.

33. In a casting machine, a nozzle for the discharge of fluid to be cast, a lifting frame movable toward and away from the nozzle in a direction parallel to its discharge, a mold carrier on the lifting frame and movable toward and away from the nozzle in a direction substantially transverse to the discharge therefrom, a mold on the carrier having a separable section, a cam bar carried by the lifting frame, and connections between the cam bar and said section, whereby the latter may be moved during movement of the carrier relative to the frame, but is held against movement while the frame carries the mold toward said nozzle.

34. In a casting machine, a crucible, a mold movable toward the latter to receive the discharge therefrom and away from the latter to expose the mold, and a shield reciprocable in a straight line path and movable into the path of the mold after the latter is positioned to receive the discharge from said nozzle and movable out of such path before the mold returns to the second-named position.

35. In a casting machine, a crucible, a mold carrier movable from a position to one side of said crucible to a position beneath the latter to receive the discharge therefrom, a vertically reciprocable shield movable into the path of the mold before such discharge and out of said path after such discharge, and means to reciprocate the shield and having a pivotal connection therewith, whereby the shield may be swung outwardly to expose the mold, if desired.

36. In a casting machine, a crucible having a discharge nozzle, a mold movable to and from a position to receive the discharge therefrom, a valve to open and close the nozzle, and a swinging drip collector automatically movable in under the nozzle as the mold moves away from it and away from the nozzle as the mold moves in under the latter.

37. In a casting machine, a crucible having a discharge nozzle, a mold movable to and from a position to receive the discharge therefrom, a valve to open and close the nozzle, and a drip collector automatically movable in an arc-like path in under the nozzle as the mold moves away from it and away from the nozzle as the mold moves in under the latter, said collector comprising a trough to convey the drippings away from the path of the mold.

38. In a casting machine, a crucible having a discharge nozzle, a mold movable to and from a position to receive the discharge therefrom, a valve to open and close the nozzle, and a pivoted shield having a drip collector thereon and automatically movable in

under the nozzle as the mold moves away from it and away from the nozzle as the mold moves in under the latter.

39. In a casting machine, a crucible having a discharge nozzle, a mold carrier movable to and from a position to receive the discharge therefrom, and a shield pivoted to swing about a horizontal axis and arranged to be engaged and moved by said carrier as it moves into position in under the nozzle.

40. In a casting machine, a discharge nozzle for the fluid to be cast, a mold adapted to be moved toward and clamped against the nozzle, and a wiper plate controlled by the movement of the mold and reciprocable across the end of the discharge nozzle to clean the same prior to the clamping of the mold thereagainst.

41. In a casting machine, a discharge nozzle for the fluid to be cast, a mold carrier movable to and from the nozzle, a reciprocable wiper actuated by the mold carrier for movement across the nozzle to clean the latter, and automatically operated means for returning the wiper to its initial position.

42. In a casting machine, a discharge nozzle for the fluid to be cast, a mold provided with an opening and adapted to be moved toward and clamped against the nozzle, and a wiper plate movable across said nozzle to clean the same and provided with an opening through which a portion of the mold may project when the mold opening is brought into registry with said nozzle.

43. In a casting machine, a discharge nozzle for the fluid to be cast, a mold provided with an opening and adapted to be moved toward and clamped against the nozzle, a wiper plate movable across said nozzle to clean the same and provided with an opening through which a portion of the mold may project when the mold opening is brought into registry with said nozzle, and automatically operable means for returning said wiper plate to its initial position.

44. In a casting machine, a discharge nozzle, a mold carrier movable toward and away from the nozzle, a mold on the carrier having separable sections, means to separate such sections when the carrier moves away from the nozzle, and means operable after the sections have separated to emit jets of fluid under pressure and arranged so that such jets impinge on the interior surfaces of the mold sections.

45. In a casting machine, a discharge nozzle, a mold carrier intermittently movable toward and away from the nozzle, a mold on the carrier having separable sections, means to separate the sections so that the mold is opened when the carrier is at rest in the second-named position, fluid pressure means to clean the separated mold sections, and controlling means

for the last-named means operable by movement of the carrier.

46. In a casting machine, a discharge nozzle, a mold carrier intermittently movable toward and away from the nozzle, a mold on the carrier having separable sections, means to separate the sections so that the mold is opened when the carrier is at rest in the second-named position, fluid pressure means 10 to clean the separated mold sections, and controlling means for the last-named means operable by movement of the carrier and arranged to actuate the fluid pressure means while the carrier is at rest in the second-15 named position.

47. In a casting machine, a crucible for the fluid to be cast having an outwardly diverging open end of materially greater area than the fluid receiving portion of the 20 crucible, a cover to close such end having a

chamber to which fluid under pressure is supplied, and outlets for such chamber opening into the said end of the crucible near the outwardly flaring walls, whereby the fluid under pressure impinges on such walls 25 and is deflected away from the fluid to be cast.

48. In a casting machine, a crucible for the fluid to be cast, a valve to control the discharge of fluid from the crucible, a mold carrier, means to move the latter toward and away from the crucible, means to operate said valve, a common driving mechanism for both said means, automatic means to stop said mechanism at the end of each cycle 30 of operation of the carrier moving and valve operating means, and manually releasable means to stop said mechanism at any point in such cycle of operation.

ALBERT W. MORRIS.
